UNITED STATES PATENT OFFICE

GEORGE F. BIBB, OF TROY, NEW YORK, ASSIGNEE TO RUUD MANUFACTURING COMPANY, OF PITTSBURGH, PENNSYLVANIA, A CORPORATION OF NEW JERSEY.

STOKING-DOOR FOR FURNACES, &c.

1,220,718.

Specification of Letters Patent. Patented Mar. 27, 1917.

Application filed September 8, 1915. Serial No. 49,419.

To all whom it may concern:

Be it known that I, GEORGE F. BIBB, a citizen of the United States, and resident of Troy, in the county of Rensselaer and State 5 of New York, have invented certain new and useful Improvements in Stoking-Doors for Furnaces, &c., of which the following is a specification.

This invention has particular reference to 10 a stoking door for garbage incinerating furnaces, and the primary object is to provide means for protecting the door proper and its hinge from contact with the refuse, and to insure discharge into the incinerator upon 15 closing the door of matter that may become lodged on either movable or fixed portions of door structure when the door is open.

The invention is embodied in a chute forming apron which is movable with the 20 door and when the latter is open directs inwardly the garbage, etc. The improved attachment also fully protects the door and its hinge, all liquid or semi-liquid matter being carried thereby inwardly over the hinge 25 joint so that there can be no leakage and no obstructing of the hinge. When closing the door, the inward movement of the attachment operates to clear the door ledge of 30 matter lodged thereon, and its own steep inclination when closed results in dislodging any matter that may stick thereon when 35 open.

It is further characteristic of the invention that the improved attachment serves 40 to define the opening movement of door and holds it in chute-forming position.

In the accompanying drawing, Figure 1 is a view in top plan of the door frame and door together with a portion of a furnace 45 or stove structure to which the frame is applied, the door being in open position. Fig. 2 is a vertical sectional view taken on line 2—2 of Fig. 1. Fig. 3 is a view similar to Fig. 2 with the door in closed position.

Referring to the drawings, 2 designates 50 the outer casing or jacket of an incinerator, stove or other like structure, and secured thereto is the door frame 3 which has the sloping front face 4 through which the door opening is formed. In the adaptation shown, the incinerator is provided with the spaced lining 5, with an opening there-through shaped and flanged to form an inward continuation of frame 3, the ledge-forming bottom portion 6 thereof prefer-

ably sloping inwardly and downwardly in continuation of the sloping ledge 7 of frame 3.

The door 8 is adapted to close flatly against frame-face 4, being mounted to rotate about a horizontal axis. In the present embodiment this axis is located at the lower side or edge of the door and is defined by the horizontal trunnions 9 which are mounted in the upwardly open hook-like bearing 65 lugs 10 at opposite sides of frame 3.

An inwardly extending apron is movably mounted on the inner side of the door and consists of the flat bottom portion 11 having at either side the upstanding wall-forming 70 parts 12. The apron is hinged at its upper end at 13 to the upper portion of the inner side of the door. When the door is open the free portion of apron bottom 11 bears flatly on the inner face of the door, and extends 75 over the hinge joint and onto frame ledge 7. Fluid or semi-fluid matter is thus directed inwardly and prevented from leaking through the hinge joint and from obstructing or clogging the hinge. In fact, all portions of the door are protected, none of the 80 surfaces thereof being exposed to the garbage, refuse or other matter with which the incinerator is charged.

The apron moves freely through the door 85 frame as the door opens and closes, and the opening movement of the latter is limited by the engagement of the upper extremities 14 of walls 12 with the top flange 15 of the frame opening, thereby holding the door 90 and apron in chute-forming position and in effect constituting said parts a hopper for receiving and directing inwardly the garbage or other matter with which the incinerator is charged. Upon moving the door 95 from the open position of Fig. 2 to the closed position of Fig. 3, the hinged apron slides inwardly over ledges 7 and 6 and overhangs the inner edge of the latter at a steep incline, thereby dislodging and directing inwardly any matter that may have become lodged thereon. The door is thus self-clearing 100 each time it is closed.

Walls 12 are notched downwardly at 16 to facilitate removal of the apron-carrying 105 door, to accomplish this, it being only necessary to partially close the door from the position shown in Fig. 2; whereupon sufficient clearance is had for the upward movement of walls 12 to enable trunnions 9 to 110

clear the open-top bearings 10, thus freeing the door and its apron from the frame.

While the invention is designed primarily as a stoking door for a garbage incinerator, it will be understood that it may be utilized in other furnace and stove structures or wherever a filling or charging door structure is required.

I claim:

10. 1. The combination of a door frame, a door for the frame mounted to open into chute-forming position, an apron movably mounted on the door and extending into the frame for directing matter thereinto when the door is open, and stops on the frame engaged by the apron for holding the door in open position.
20. 2. The combination of a door frame having its open face sloping in a direction to maintain the door closed by gravity, a stoking door adapted to close against said face and mounted at its lower side to rotate about a horizontal axis, an apron hinged to the inner side of the door and movable through the frame opening as the door opens and closes, and means on the apron for limiting the opening movement of the door to provide a chute.
30. 3. The combination of a door frame, a door for the frame mounted to swing outwardly and downwardly, an apron having bottom and side walls, the apron hinged at one end of its bottom wall to the inner side of the door and with the free portion of the apron entered in the frame when the door is open, and stop means on the frame engaged by the side walls of the apron for

limiting the opening movement of the door and apron.

4. The combination of a door frame, a door for the frame mounted to swing outwardly and downwardly into inclined position, an apron hinged to the upper portion of the inner side of the door and consisting of an imperforate bottom and imperforate opposite upstanding side walls, said apron bottom and side walls projecting into the frame when the door is open and with said walls extending upwardly to the top of the frame opening and adapted to engage the top portion of the frame for holding the apron carrying door in inclined open position.

5. The combination of a door frame, a door therefor mounted to rotate at its lower edge about a horizontal axis, bearings on the frame for the door adapted to be disengaged by upward movement of the latter, an apron at the inner side of the door and hinged to the upper portion of the latter, upstanding walls at opposite sides of the apron movable through the door opening and extending to the top thereof for engaging the frame and limiting the opening movement of the door, the side walls recessed downwardly to permit the door and the wall carrying apron to be elevated sufficiently to release the door from its bearings.

In testimony whereof I affix my signature in presence of two witnesses.

GEORGE F. BIBB.
